UNITED STATES PATENT OFFICE

JOSEF GASSEN, OF DUSSELDORF, GERMANY, ASSIGNOR TO SCHLOEMANN AKTIEN-
GESELLSCHAFT, OF DUSSELDORF, GERMANY, A CORPORATION OF GERMANY

INGOT-PUSHING DEVICE

Application filed July 23, 1928, Serial No. 294,909, and in Germany November 4, 1927.

My invention relates to mechanism for ingot pushing devices used for introducing ingots into reheating furnaces and has for its particular object to provide a device of this kind, whereby ingots can be pushed into such reheating furnaces to a substantial depth without the use of time-consuming operations, such as the coupling of telescoping elements adapted to act on the pushing head, whereby the ingots are pushed in.

Frequently, the space available on the side of the furnace where the ingots are introduced, is not large enough to permit the elements used for this kind of work to push the ingots far enough into the furnace. In that case, it becomes necessary to use telescoping elements adapted to be extended and shortened. By means of such telescoping elements which are first coupled at one end, the ingots can be pushed into the furnace to a certain depth, but then it becomes necessary to loosen the coupling, to pull the elements apart backwards to again couple them at the other end and then push the ingots by means of the pushing head to the desired depth into the furnace. The same operation, in the reverse order, must then be repeated upon the withdrawal of the pushing head from the furnace consuming much time, during which time, the elements, as they lie idle in the furnace become very hot. According to the present invention, auxiliary screw-spindles are provided, in addition to the main screw-spindle, said auxiliary spindles carrying the pushing head adapted to act on the ingots and being so arranged that the ingots can be quickly and securely pushed into the reheating furnace to any desired depth, so that the elements used for the introduction of the ingots will not be exposed to the hot combustion gases of the furnace any longer than is required for pushing the ingots in.

In the drawing, in which I have shown, by way of illustration, an embodiment of the invention,

Fig. 1 shows the new device ready to push ingots into a reheating furnace, parts being shown in section, while Fig. 2 shows the same device with the operating elements in partly advanced position.

The principal parts of the device are the main screw-spindle 1, the stationary frame 2, the movable cross-beam 3, the nut 4 cooperating with the spindle 1, the toothed wheel 5, the toothed wheel 6, the two pinions 7, the auxiliary screw-spindle 8, adapted to be rotated by means of said pinions 7, the nuts 9 operatively engaged by said auxiliary spindles 8, the extension members 10 adapted to be operated by said nuts 9, the annular guiding members 11, and the pushing head 13 carried thereby. At 15 are shown several ingots, and at 16 is indicated the furnace. By 17 is designated the depth of introduction, while 18 designates the available space in front of the furnace 16, which space, under ordinary conditions, would not be sufficient to permit ingots to be pushed into the furnace to the required depth by means of one-piece operating elements.

The motor shown at 14 is used for rotating, by means of the pinion 20 and the toothed wheel 5, the main screw-spindle 1 which is rotatably journaled in the stationary frame 2 at 19 and 19^a. By means of the nut 4 secured to, or formed integral with, the movable cross-beam 3, the latter is moved longitudinally, as spindle 1 is rotated, as indicated in Fig. 2. In the movable cross-beam 3 is rotatably journaled the toothed wheel 6 which is keyed to spindle 1, a longitudinal groove 21 being provided therein for the key. With the toothed wheel 6 are in mesh, on either side thereof, the smaller toothed wheels 7 which are mounted at the ends of the auxiliary screw-spindles 8 rotatably journaled in the movable cross-beam 3 and which, by means of the nuts 9, cause a longitudinal movement of the extension members 10 carrying the pushing head 13. For preventing the auxiliary spindles 8 and the extension members 10 from bending, annular guides 11 are provided, which move in tubular guards 12 adapted to slide in the stationary frame 2. In view of the positive connection between the main screw-spindle 1, the auxiliary spindles 8, the extension members 10 and the pushing head 13, the path travelled by the latter, without any special coupling, is twice that of the movable cross-beam 100.

3, and the same is the case, as the spindles 8 are withdrawn from their advanced position. In this manner, the introduction of the ingots into the furnace and the withdrawal 5 of pushing head 13 are effected much more rapidly than with the telescopic mechanism heretofore used, and the various elements will not lie idle for any length of time and be exposed to the heat of the hot combustion 10 gases.

I claim:

1. In an ingot pushing device, the combination with the frame, a main operating spindle journalled therein and the pushing head, 15 of a movable part adapted to be moved back and forth along said frame by said main spindle, auxiliary spindles rotatably journalled in said movable part, and means in said frame operable by said main spindle for operation 20 said auxiliary spindles to thereby advance and retract said pushing head.
2. In an ingot pushing device, the combination with the frame, of a main operating spindle journalled therein and the pushing head, 25 of a movable cross-beam adapted to be moved back and forth along said frame by said main spindle, auxiliary spindles rotatably journalled in said movable cross-beam, means in said frame operable by said main 30 spindle for operating said auxiliary spindles, and means actuated by said auxiliary spindles so as to advance and retract said pushing head.
3. In an ingot pushing device, the combination 35 with the frame, of a main screw-spindle journalled therein and the pushing head, of a movable cross-beam adapted to be moved back and forth along said frame by said main screw-spindle, auxiliary screw-spindles rotatably journalled in said movable cross-beam, toothed wheels at the inner ends of 40 said auxiliary screw-spindles, a toothed wheel on said main screw-spindle adapted to rotate therewith and in mesh with said toothed wheels, means for rotating said main screw-spindle in either direction, and extension elements actuated by said auxiliary screw-spindles so as to advance and retract said pushing head.

50 In testimony whereof, I affix my signature.
JOSEF GASSEN.
